UNITED STATES PATENT OFFICE.

EDGAR E. PHINNEY, OF NEW YORK, N. Y., ASSIGNOR TO MONROE CALCULATING MACHINE COMPANY, OF NEW YORK, N. Y., A CORPORATION OF NEW YORK.

CALCULATING MACHINE.

1,220,545.

Specification of Letters Patent.

Patented Mar. 27, 1917.

Application filed July 22, 1915. Serial No. 41,343.

To all whom it may concern:

Be it known that I, EDGAR E. PHINNEY, a citizen of the United States, resident of New York, in the county of New York and State of New York, have made a certain new and useful Invention in Calculating Machines; and I declare the following to be a full, clear, and exact description of the same, such as will enable others skilled in the art to which it appertains to make and use the invention, reference being had to the accompanying drawings, and to letters or figures of reference marked thereon, which form a part of this specification.

15 The invention has relation to improvements in calculating machines of the type shown in the Reissue Patent No. 13,841, dated December 8, 1914, having for its object to simplify the method of procedure in 20 the performance of the different arithmetical problems, in that the crank handle is always started and stopped at the same place. A further object is to provide continuously turned operating gears, eliminating 25 intermittently turning gears, with the consequent objectionable clicking noise as the gears are engaged. A further object is to reduce the gear ratio of the selecting or 30 primary wheels to the driving gears and the registering wheels, thus reducing the power required to turn the crank handle and reducing the speed of the registering dials or 35 wheels and rendering them less liable to be overthrown. A further object is to simplify the carrying mechanism, eliminating the oscillating members thereof. All of 40 these objects are enabled to be accomplished to advantage practically by the use of eccentric gears in the driving connection, as hereinafter stated.

The invention consists in the novel construction and combinations of parts, as hereinafter set forth.

In the accompanying drawings, illustrating the invention, Figure 1 is a vertical section on the line 1—1, Fig. 2; Fig. 2 is a horizontal section on the line 2—2, Fig. 1; Fig. 3 is a section on the line 3—3, Fig. 2; Fig. 4 is a detail face view of one half or section of one of the primary or selecting wheels; Fig. 5 is a detail side view of the same; Fig. 6 is a detail face view of the other half or section of one of the primary or selecting wheels, and Fig. 7 is a detail side view of the same.

In these drawings the numeral 3 designates the operating or crank handle, 4 the shaft of the selecting or primary wheels, 5 the primary wheels, 13 the registering dials, 12 the intermediate gears, and 73 the shaft 60 of the carrying mechanism.

In accomplishing the results and advantages stated, the crank handle is turned completely in one direction, or clockwise, for addition and multiplication, and completely 65 in the opposite direction for subtraction and division, each time from the same starting point.

The primary wheels 5 have each a toothed portion extending around a portion of the 70 periphery of the wheel, and are mounted upon their shaft with the toothed portions of the wheels in substantial alinement. These primary wheels are controlled from the keyboard and operate upon the 75 registering dials as in the Reissue Patent 13,841, referred to.

Carried by the shaft 73 are a plurality of collars, *a*, *b*, *c*, *d*, *e*, *f*, *g*, *h*, and *i*, provided each with two radial arms *m*, *m*, fast 80 thereto, each radial arm being provided with a carrying pawl or dog *j*. All of said collars are fixed upon the shaft, and the carrying pawls are arranged in two oppositely pitched spiral lines, each series or 85 set of pawls extending about one-fourth around the shaft, both together about one-half around, and the two series nearly intersecting or ending adjacent to each other. These carrying pawls are actuated by plun- 90 gers seated in the shaft of the intermediate gears 12, and operate the registering dials through said gears, as fully described in the Reissue Patent 13,841, hereinbefore mentioned.

The crank handle being turned as stated, the shaft of the carrying mechanism will be turned completely therewith, by means of the train of spur gears 76, 75, 74 and two members of a sub train of gears 10, 11, 12, the gear 11 being located upon a short shaft 74' of and turning with the gear 74, and being the middle gear of said sub train, the gear 10 being fast upon the shaft of 100 the selecting wheels and the gear 12 being fast upon the shaft of the carrying mechanism, whereby the shaft of the selecting wheels will be also turned constantly 105 throughout the movement of the crank handle.

The gears 10, 11, and 12 are eccentrically mounted upon their shafts, the selecting wheels thereby turning at greater speed during the second and third quarters of their revolution, or when in mesh with the intermediate gears, and at less speed during the first and fourth quarters, when being moved into and away from operative position, or when the carrying mechanism is in operation, and the carrying mechanism turning at greater speed when in operation, or during the last quarter of its revolution in either direction.

In other words, the operation of the eccentric gears is so timed that during the first quarter revolution of the crank handle, the toothed section of the selecting wheel is rotated slowly into mesh with the intermediate gear; during the next half revolution of the crank handle the selecting wheel is rotated at high speed, in mesh with the intermediate gear, and during the last quarter revolution the selecting wheel is returned slowly to initial position. So, also, during the first quarter revolution of the crank handle, one series of carrying pawls will be moved rapidly past the intermediate gears, the plungers of which are not set for carrying; during the next half revolution of the crank handle, or while the selecting gears are in operative engagement with the intermediate gears to turn the same and set the plungers thereof for carrying, the carrying shaft and pawls will be moved slowly and the other series of carrying pawls will be brought around into operative position, and during the last quarter revolution, or while the carrying is being performed, the selecting wheels will be out of engagement with the intermediate wheels, and said other series of carrying pawls will be moved rapidly, in operative engagement with the plungers of the intermediate gears.

And inasmuch as the operation of each series of carrying pawls ends short of the intersection of the two oppositely pitched spiral lines, a return arm or arms 14 for the plunger relating to each intermediate wheel is enabled to be fixedly mounted upon the carrying shaft, midway between the two series of carrying members, said arm being oppositely beveled at 14', to return all of the plungers of either series simultaneously to normal position in either direction of rotation of the carrying shaft.

The selecting wheels being rotated slowly while the carrying mechanism is being rotated rapidly, and vice versa, the strain upon the operating shaft or crank handle is rendered even and balanced at all times during the turning thereof, facilitating accuracy and ease of operation. An eccentric gear being located upon the shaft of the carrying mechanism, as well as upon the shaft of the selecting wheels, the eccentricity and the

consequent variation in speed is enabled to be made less than if there were an eccentric gear provided upon one of these shafts alone, in train with an eccentric gear upon the shaft of one of the larger spur gears.

What I claim is:

1. In a calculating machine, registering wheels, selecting wheels and carrying members actuating the registering wheels, an operating shaft, and a continuous drive connection between said operating shaft, said carrying members and said selecting wheels, involving means for obtaining variable speed.

2. In a calculating machine, registering wheels, selecting wheels and carrying members actuating the registering wheels, an operating shaft, and a continuous balanced variable speed drive connection between said operating shaft, said carrying members and said selecting wheels.

3. In a calculating machine, registering wheels, selecting wheels and carrying members actuating the registering wheels, an operating shaft, and a continuous drive connection between said operating shaft, said carrying members and said selecting wheels, involving eccentrically mounted gears for obtaining variable speed.

4. In a calculating machine, registering wheels, selecting wheels, carrying members, intermediate gears, an operating shaft, a continuous drive connection between said operating shaft, said carrying members and said selecting wheels, involving a train of gears, a gear mounted eccentrically upon the shaft of the selecting wheels and a gear mounted eccentrically upon the shaft of one of the gears of said train, meshing with the first-named eccentrically mounted gear.

5. In a calculating machine, registering wheels, selecting wheels and carrying members actuating the registering wheels, an operating shaft, and a continuous variable speed drive connection between said operating shaft, said carrying members and said selecting wheels, involving a train of gears, a gear mounted eccentrically upon the shaft of the selecting wheels, a gear mounted eccentrically upon the shaft of the carrying members and a gear mounted eccentrically upon the shaft of one of the gears of said train, meshing with the first named eccentrically mounted gears.

6. In a calculating machine, registering wheels, selecting wheels and two spiral series of carrying members actuating the registering wheels, said series extending in opposite directions around their shaft and ending adjacent to each other, and an operating shaft having a continuous drive connection with said carrying members and said selecting wheels and having invariably the same starting and stopping point.

7. In a calculating machine, registering

- wheels, selecting wheels and two spiral series of carrying members actuating the registering wheels, said series extending in opposite directions around their shaft and ending adjacent to each other, and an operating shaft having a continuous drive connection with said carrying members and said selecting wheels, involving eccentrically mounted gears and having invariably the same starting and stopping point.
8. In a calculating machine, registering wheels, selecting wheels, two spiral series of carrying members, intermediate wheels, reciprocating plungers operated by the registering wheels, said series extending in opposite directions around their shaft and ending adjacent to each other, an operating shaft having a continuous drive connection with said carrying members and said selecting wheels and having invariably the same starting and stopping point, and means for returning the plungers to normal position, located midway between the two series of carrying members.
9. In a calculating machine, registering wheels, selecting wheels, two spiral series of carrying members, intermediate wheels, said series including arms all of which are fixed to their shaft and pawls carried by said arms and operating in planes parallel to said shaft, both series extending in opposite directions around their shaft and ending adjacent to each other, and an operating shaft having a continuous drive connection with said carrying members and said selecting wheels, involving eccentrically mounted gears and having invariably the same starting and stopping point.
10. In a calculating machine, registering wheels, selecting wheels, two series of carrying members, intermediate wheels, reciprocating plungers operated by the registering wheels, an operating shaft, and a continuous drive connection between said operating shaft, said carrying members and said selecting wheels, arranged to, upon the first quarter rotation, turn one series of carrying members out of the way, upon the next half rotation turn the intermediate gears, through engagement therewith of the selecting wheels, and upon the last quarter rotation turn the other series of carrying members into operative engagement with said plungers, to perform the carrying.
11. In a calculating machine, registering wheels, selecting wheels, two series of carrying members, intermediate wheels, reciprocating plungers operated by the registering wheels, an operating shaft, and a continuous drive connection between said operating shaft, said carrying members and said selecting wheels, involving eccentrically mounted gears arranged to, upon the first quarter rotation, turn one series of carrying members out of the way, upon the next half rotation turn the intermediate gears, through engagement therewith of the selecting wheels, and upon the last quarter rotation turn the other series of carrying members into operative engagement with said plungers, to perform the carrying.

In testimony whereof I affix my signature, in presence of two witnesses.
